UNITED STATES PATENT OFFICE.

JACOB P. SIMON, OF BEAUMONT, TEXAS.

ROOF STRUCTURE.

1,283,338.

Specification of Letters Patent. Patented Oct. 29, 1918.

Application filed August 21, 1914. Serial No. 857,918.

To all whom it may concern:

Be it known that I, JACOB P. SIMON, a citizen of the United States, residing at Beaumont, in the county of Jefferson and 5 State of Texas, have invented certain new and useful Improvements in Roof Structures, of which the following is a specification.

An object of my invention is to provide a 10 building constructed to have movable panels in the roof and side walls thereof constructed to permit of manual adjustment to regulate the temperature, light, and moisture within the building for any desired purpose such as the growing of plants, to provide ventilation for the building, and in other connections.

A further object is to so hinge and balance the panels that the same may be opened or 20 closed quickly and with ease whenever desired.

A still further object is to construct the rafters and studding of the building to be a framework and so connect the panels there- 25 with that these panels can be easily and quickly put up or taken down, which may be desirable when the houses contain plants which require protection only during the winter, and stowed away out of the weather 30 or placed over other houses to protect plants contained therein in the summer from excessive rains or heat.

With other objects in view, which will be referred to, my invention consists in the pec- 35 culiar combination and novel arrangement of parts, such as will be hereinafter more fully described in connection with the accompanying drawings and more particu- larly pointed out in the appended claims.

40 In the drawings:—

Figure 1 is a view in parallel perspective looking from one end of the building constructed after my invention and with the near end of the building removed or left 45 open.

Fig. 2 is a view in bottom plan of a section of the roof of the building with the panels thereof indicated in the tilted or opened position.

Fig. 3 is a fragmentary detail perspective 50 view of a portion of the roof structure.

Fig. 4 is a detail perspective view to better illustrate the form of one of the roof rafters.

The frame of the building comprises the 55 sills or timbers 1, 1 which are mounted to support the end walls and are connected with the sills or timbers 2, 2 which locate the point at which the sides are to be disposed. The studs 3, 3 are mounted on the sills 1 and 60 2 and the plates 4, 4 are secured on the upper end of the studding. The rafters 5 and 6 are secured to the plates above the side sills 2 and at their inner ends are secured together to form a ridge-roof supporting struc- 65 ture.

A ridge board 7 is secured across the several roof rafters 5 and 6 at their point of connection at the inner end to support the rafters in the proper spaced relation and to 70 also form a weather-proof ridge, and the boards 8 are secured across the rafters at the eaves of the roof structure. The several parts as hereinbefore described may be of metal, of wood, or of other suitable mate- 75 rial and the manner of construction and assembly as described is merely one of several which will very readily adapt itself to this invention.

Panels 9, the structure of which is better 80 disclosed in Figs. 2 and 3, have the eyelets 10, 10 secured in a line along the approximate transverse center of the lower side thereof and the hook members 11, 11 are carried by the rafters 5 and 6 to be engaged 85 through these eyelets or staple members 10, and to hold the panels nearly balanced thereon and in a relation to be capable of swing- 90 ing movement around the hooks. An operating rod 12 has a flexible link 12' connect- 95 ing it with each of said panels 9 near one of the side edges thereof, and this operating rod underlies the rafters at right angles thereto so that upon endwise shifting move- ment thereof the several panels will be 95 swung to the position indicated in Figs. 1 and 2, then by reversing the direction of movement of the operating rod 12, the panels

will be brought to the closed position and will be held in this position against individual and accidental opening. A bracket 13 is carried by the frame of the building and an operating lever 14 is pivoted near its center to this bracket and at its upper end is pivotally connected at 15 with the operating rod 12 so that swinging movement given to the lower end of the rod by the operator will 10 cause a shifting of the operating rod 12 to open and to close the panels 9 in their swing-ing relation.

The wall panels 16, 16 are hinged or 15 swung on the studs 3 to be capable of move-ment in a swinging path as has been set forth in connection with the panel members 9. The operating rod 17 may be connected by the links 18 with the panels 16 and then 20 upon endwise shifting movement of this operating rod 17, the several panels will be 25 swung simultaneously to the open or closed position as the rod may be shifted in the one direction or the other.

It is preferable that each of the roof 25 panels 9, as better illustrated in Fig. 3, be provided at the end, on that portion which swings above the roof rafters, with the over-lapping flap 19 which will fit down against the eave board 8 and thus provide a weather-30 proof joint in that portion of the structure and the remaining portion of the same end of the panel 9 is formed in an upturned flange 20 which will direct the water caught by the roof to flow down over the flap 19 35 and at the same time will permit the free swinging movement of the panel. To provide a weather-proof joint between the several panels at the side edge thereof, flaps 21 are secured on the upper side of the edges of 40 the panels adapted to rise above the roof rafters, and when the panels are closed the flaps 21 will swing down over the free edges of the next adjacent panels and the flap will act as a batten to prevent water passing 45 through the roof structure at the joint be-tween the panels.

While no particular material has been mentioned as used in the construction of the wall and roof panels, yet it is perhaps desir-50 able that these panels be made of sheet metal and if the occasion would seem to demand, the panels may take the form of metal frames which can have glass panes mounted therein to form windows or the entire num-55 ber of panels may have these glass windows provided therein and the building can thus be adapted for use as a greenhouse. As is illustrated in Fig. 2, the panels may be 60 swung to extend at right angles to the line in which studs and rafters are placed and with the panels in this position the structure will present virtually a mere frame, then again the panels may be set at any desired angle and the amount of light and air per-65 mitted to pass into the building can be regu-

lated, further the panels may be entirely re-moved from the frame structure and the building may thus be opened during the summer to permit the natural growing of plants which require protection during more 70 severe weather and in other connections the temperature, light, and moisture may be regulated inside the building by an adjust-ment of the panels, or two sets of panels may be provided and may be interchanged to suit 75 the condition of operation and climatic changes.

From the foregoing it will be seen that I have provided a building which is very sim-80 ple manufactured and constructed and which will permit a regulation and adjust-ment of the parts to vary the temperature, light, moisture, etc., within the building with respect to these conditions on the exterior, also it will be seen that the building is one 85 which is capable of variation in the con-struction and which may thus be adapted to a great number of various uses.

While I have herein shown and described one specific form of my invention, it will be 90 understood that slight changes might be made in the form and arrangement of the several parts of the structure without de-parting from the spirit and scope of my in-vention, and hence I do not wish to be lim-95 ited thereto except for such limitations as the claims may import.

I claim:

1. In a building, the combination with 100 parallel spaced rafters, a ridge board over-lying their upper ends, and an eave board overlying their lower ends; of roof panels respectively overlying the rafters, one for 105 each, a row of eyes on the underside of each panel at its transverse center, a row of hooks along the rafter loosely engaging said eyes, a rod underlying the rafters at right angles thereto, links connecting the rod with one 110 edge of the respective panels for swinging them simultaneously on their hinge connec-tion with the rafters, a flap projecting from 115 the lower end of each panel on that half which rises and adapted to overlie said eave board, a flange projecting from the other half of the lower end and adapted to pass 120 said eave board when the panel is turned on its support, a flap secured along the edge which rises and adapted to overlie the next adjacent pane, and means for operating said rod.

2. In a building, the combination with 125 parallel spaced rafters, a ridge board over-lying their upper ends, and an eave board overlying their lower ends; of roof panels respectively overlying the rafters, one for 130 each, a row of eyes on the underside of each panel at its transverse center, a row of hooks along the rafter closely engaging said eyes, a rod underlying the rafters at right angles thereto, links connecting the rod with one 135

edge of the respective panels for swinging them simultaneously on their hinge connection with the rafters, a bracket within said building structure, and an operating rod 5 fulcrumed on said bracket and connected with said first-named rod, for the purpose set forth.

In testimony whereof I affix my signature in presence of two witnesses.

JACOB P. SIMON.
